UNITED STATES PATENT OFFICE.

HARRY C. DOWNEY, OF SPRINGFIELD, OHIO.

SADIRON.

Application filed January 3, 1922. Serial No. 526,657.

To all whom it may concern:

Be it known that I, HARRY C. DOWNEY, a citizen of the United States, residing at Springfield, in the county of Clark and State of Ohio, have invented certain new and useful Improvements in Sadirons, of which the following is a specification.

My invention relates to improvements in sad irons of the self-heating type, and particularly of the kind which are heated by apparatus employing liquid fuel incorporated as a part of the iron structure

The object of my invention is to improve the heating apparatus to secure a more perfect combustion of the fuel; a more specific object being to improve the generating portions of the apparatus to thereby obtain an efficient vaporization of the liquid fuel.

Further objects will appear from the accompanying description and claims.

In the accompanying drawings:—

Fig. 1 is a longitudinal section of a device embodying my improvements.

Fig. 2 is a longitudinal section of the heating apparatus.

Referring to the drawings, 1 represents the main body portion of iron, formed with an inner chamber and having a cover 2, removably secured thereto in any well known way; the cover having the usual handle 3. A member 4, similar in most respects to that shown in Letters Patent No. 996,942 dated July 4, 1911, is inserted in an opening in the rear wall of the body 1, this member having side grooves 4^a engaged by the side walls of the opening in a manner explained in said patent. This member 4 has communicating passages 5 and 6 controlled by the valve 7 and the lower end of the passage 6 has leading therefrom a small jet opening 8, spaced from the open end of a burner tube 9, supported by the apron 10 on the member 4 substantially as shown in the prior patent.

In the present case, the forward end of the member 4 has an exteriorly threaded boss 4^b upon which is threaded the rear end of a tube 11, which extends along the upper side of the burner tube in close proximity thereto. The forward end of the tube 11 has threaded therein the rear end of a supply tube 12 which is supported by the forward wall of the body 1 and carries a fuel tank 13, constructed in the manner shown in the prior patent referred to in that it has a nip-

ple 14, the upper end of which is closed by a cap 15, the nipple extending into the tank for the purposes explained in said patents. 55

A difficulty heretofore met with in devices of the character has been the lack of proper combustion, which not only causes a disagreeable odor but also insufficient heating capacity for ironing purposes, this trouble being due to the fact that the area of the generating parts of the apparatus were too restricted to at all times vaporize the liquid fuel to the proper degree necessary for good results. In my improved structure it will be noticed that the interior diameter of the tube 11 is of considerably greater dimension, substantially three times greater, than that supply tube 12 and that of the passages 5 and 6 which supply tube and passages are of the usual and proper dimensions found in devices of this character, and that this tube is located immediately above the burner, as a result of which the liquid is generated more rapidly and in sufficient quantity to furnish ample gas in a highly vaporized condition to provide a good combustible mixture to the burner. By having the supply tube 12 of comparatively small dimensions as compared with the generator tube, undue back pressure sufficient to endanger the tank is prevented. As clearly shown in Fig. 2 the relative proportion of the diameter of the tube 11 and the supply tube 12 is an important feature of the invention and should be at least in the ratio of three to one, that is to say, the supplementary chamber or tube 11 should be at least three times larger in diameter than the supply tube 12. In practice it has been found that this chamber can even be made relatively larger in diameter than the foregoing portions, but if reduced to the ratio of anything approaching the same size as the supply tube 12 the device will not operate properly.

This arrangement has been found in practice to be most efficient, as it is possible and is the practice by this method to alter the heating apparatus of old irons returned because of inefficient service, so as to convert them into efficiently working devices with no other change than the installation of the improved form of generator described. 100 105

The arrangement also acts as a trap to arrest particles of foreign matter to prevent clogging of the jet, these foreign parti-

cles settling on the bottom of the generator tube; it being observed that the bottom of the tube is below the outlet therefrom.

It has been further found in practice that 5 a more uniform pressure of gaseous vapor is secured than in the old devices, thus maintaining a flame of uniform intensity.

Having thus described my invention, I claim:—

- 10 In a device of the character described, the combination of a main body portion having a chamber, a member supported at one end of said chamber having a horizontal passageway and a connecting vertical passageway, a jet formed near the end of the verti-

cal passageway, an unobstructed generator tube in said chamber communicating at one end with said horizontal passageway, a fuel supply tube for said generator tube, the generator tube being formed of a diameter substantially three times the diameter of the supply tube, a fuel tank supported at the upper end of said supply tube, and a burner tube supported beneath and in parallel relation with said generator tube for the purpose 20 25 specified.

In testimony whereof, I have hereunto set my hand this 12th day of December 1921.

HARRY C. DOWNEY.
